UNITED STATES PATENT OFFICE.

JESSE A. CRANDALL, OF BROOKLYN, NEW YORK.

CHILD'S CARRIAGE.

SPECIFICATION forming part of Letters Patent No. 280,454, dated July 3, 1883.

Application filed October 30, 1882. (No model.)

To all whom it may concern:

Be it known that I, JESSE A. CRANDALL, of Brooklyn, in the county of Kings and State of New York, have invented an Improvement in 5 Parasol Attachments for Children's Carriages, of which the following is a specification.

Figure 1 is a side view of my improvement in parasol attachments for children's carriages. Fig. 2 is a vertical section on an enlarged scale, 10 showing the manner of connecting the post to the back of the carriage-body. Fig. 3 is a horizontal section on the plane of the line *c c*, Fig. 2. Fig. 4 is a detail vertical section, on an enlarged scale, through the joint between the 15 post and the bow that carries the parasol. Fig. 5 is a bottom view of the top plate of said joint, and Fig. 6 a top view of the bottom plate thereof.

This invention relates to a new manner of 20 joining the post of a parasol attachment for children's carriages adjustably to the carriage-body.

The invention is applicable to such structures as are described in Letters Patent No. 25 241,122, of May 10, 1881, and to other parasol attachments; and it consists, first, in combining with the notched lower part of the post a certain slotted supporting-arm that projects from the carriage-body, and a movable latch 30 or bolt that enters into one of the notches and holds the post firm at any desired elevation, and a combined rest and guide for said latch and said post.

In the drawings, the letter *A* represents the 35 post, and *B* the bow or parasol-holder of the attachment. The post *A* is connected to the carriage-body *D* by a bracket, *C*. This bracket *C* is more fully shown in Figs. 2 and 3, and consists of a face-plate, *a*, that is fastened to 40 the carriage-body by means of screws or otherwise, and of a projecting arm, *b*, which extends horizontally, or nearly so, from the carriage-body. This arm *b* is perforated vertically, or nearly so, at two places. The perforation near its outer end serves to admit the 45 post *A* through it, as shown in Fig. 2, and near the other end is pivoted in the other perforation to the bracket a latch or lever, *d*, which ordinarily rests on a bridge or support, 50 *e*, which is formed in the arm *b* and separates

said two perforations. The post *A* has series of notches or indentations, *f*, on that side which faces the latch *d*. The post *A* at that portion which enters the bracket is of suitable cross-section other than a circular cross-section, so that it cannot revolve in the bracket. It is properly guided in the walls of the outer slot, of which the bridge *e* forms one wall. The free end of the latch *d*, entering one of the indentations *f* of the post *A*, will 55 have the effect of holding the post at any desired elevation and with it the parasol attachment, so that the parasol can be let down or raised up, as occasion may require. Normally, the latch rests on the bridge *e*, as 60 shown. When the child is sleeping or lying down, the parasol can be lowered, and when the child is seated in the carriage the parasol can be raised.

Heretofore the posts of vertically-adjustable 70 parasol attachments were clamped in place by means of screws, which were liable to give out in their threads, and render the entire attachment useless. By my invention the adjustment is rendered very easy, and not liable to 75 get out of order at any time, and the post is always held steady.

In order to adjust the post in the bracket, it is first slightly lifted, so as to carry the latch *d* slightly over the bracket or arm *b*, and then 80 the latch is taken out of the notch and the post adjusted to bring another notch into line with the latch.

The upper end of the post *A* has an enlargement or plate, *h*, on which rests an enlargement or plate, *i*, that is formed at the end of the bow *B*, and these two enlargements or plates *h* and *i* are connected by a screw and nut, *j*, as shown in Figs. 1 and 4, and as substantially described in said Letters Patent No. 241,122.

l is a projecting button or pin (see Figs. 4 and 6) on the contact-face of one of these plates, (in the example shown on plate *h*.)

m m are a series of indentations or recesses 95 on the contact-face of the opposite plate, (in this example plate *i*.) so that the button or projection *l* must enter one of said indentations, thereby holding the bow in the desired position and preventing it from turning on the 100

screw *j*. When it is desired to adjust the position of the bow, the screw must be loosened, the plate *i* lifted off the button *l* and turned sufficient to bring another indentation *m* over 5 the button, whereupon the joint is again rigidly closed.

I do not claim a bracket having outwardly-projecting ears for holding a latch.

I claim—

10 The bracket *C*, having two apertures divided by the bridge *e*, and combined with the notched

post *A*, that passes through the outer aperture, and with the latch *d*, hinged in the inner aperture, the bridge *e* serving to steady the post and also as a rest for said latch, substantially as herein shown and described. 15

This specification of my invention signed by me this 28th day of October, 1882.

JESSE A. CRANDALL.
